FURNACE LOADING APPARATUS

Raymond F. Newell and George W. Hegel, Schenectady, N. Y., assignors to General Electric Company, a corporation of New York

Application July 31, 1935, Serial No. 34,008

1 Claim. (Cl. 214—26)

Our invention relates to apparatus for loading a furnace of the conveyor type and is particularly adapted for use when the work to be loaded on the conveyor in the furnace comprises many 5 relatively small parts. It is the object of our invention to provide an improved loading apparatus for such a furnace by which small articles which are to be treated in the furnace may be loaded on the conveyor with a relatively even 10 distribution. Another object of our invention is to provide a loading apparatus with which a furnace of the conveyor type having a protective atmosphere may be loaded without undue loss of the atmosphere and without a material dilution 15 thereof with air.

Referring to the drawing, Fig. 1 is a side elevation of a portion of a furnace including an embodiment of our invention; Fig. 2 is a top view of the embodiment; and Fig. 3 is a perspective view 20 drawn to a larger scale and showing the under portion of the loading tray forming a part of the embodiment.

In the drawing we have represented at 1 a portion of a furnace of the conveyor type wherein 25 in the conveyor 2, which for example may be a mesh belt, is shown supported by the drum or sprocket 3 at one end of the furnace. By suitable and well known means, not shown, the drum 3 is rotated in the direction shown by the arrow, 30 and at a speed such that the articles resting upon the conveyor are subjected to the desired heat treatment while passing from the one drum 3 to a corresponding drum at the opposite end of the furnace. In order to admit work to the 35 furnace to be treated therein the furnace is provided with the opening 5 in the wall thereof, and opposite this opening is the gate extension 6. The gate 7 fits in the extension 6 in order to effectively close the opening to prevent an undue 40 loss of a protective atmosphere when such is used in the furnace and to prevent the entrance of air into the furnace. To facilitate the closing and opening of the gate 7 it is shown suspended by the cable 8, which passes over pulley 9 to the 45 counterweight 10.

Arranged opposite the conveyor and in front of the opening in the furnace is the track 12 which is represented in Fig. 2 as comprising two spaced horizontal members, such for example as 50 channel bars, which are shown supported by the vertical member 13 which may be channel bars or other structural members. Arranged between the members forming the track is the carriage 15 shown as comprising the side bars 16 and the 55 transverse bars 17. This carriage is supported

by the flanged wheels 18 which are located at the rear portion of the carriage and are arranged to engage the flanges of the channel bars forming the track, the carriage being adapted to be moved by the handle 19. At the opposite or 5 front end of the carriage is the tray 20 into which are placed the articles to be loaded on the conveyor. The tray is fixed to the carriage but the bottom 21 of the tray is slidably mounted in the side walls whereby it may be withdrawn or slid 10 rearwardly in order to drop the articles contained by the tray on the conveyor. For moving the bottom 21 of the tray relative to the tray itself, we have provided the rod 22 which extends through the transverse members 17 of the carriage and 15 has the handle 23 secured to it near the rear portion of the carriage whereby the operator may withdraw the bottom after the carriage with the loaded tray has been pushed to its forward position bringing the tray over the conveyor. In 20 order to avoid the danger of small parts of the work falling off the side of the conveyor when the bottom of the tray is withdrawn, we have provided the tray with the side extensions 24 whose 25 depth is nearly sufficient to touch the conveyor. To insure that the articles or parts being loaded into the furnace shall be evenly distributed on the conveyor when the bottom of the tray is withdrawn, we have provided the tray with a number 30 of transverse partition-like members 25 which divide the tray into a series of narrow sections into which small articles, represented at 26, to be treated, are placed.

In the use of this apparatus the operator will 35 load the various sections of the tray with the articles when it is in the position illustrated by Fig. 1, that is, outside of the furnace, taking care not to load the articles in the tray to a greater depth than what is desired on the conveyor. He will then raise the furnace door 1 and immediately 40 push the carriage 15 forward to bring the tray directly over the conveyor to the position indicated by the dotted lines in Fig. 1. By grasping the handle 23 and moving it rearwardly the bottom of the tray is withdrawn and the articles in 45 the several sections between the transverse members 25 will be dropped on the conveyor with substantially the same distribution as they have in the tray. The carriage is then quickly withdrawn from the furnace and the gate immediately lowered. The operator then proceeds to refill the tray and repeat the operation.

In Fig. 1 we have shown a simple signal device 50 to notify the operator when the conveyor has moved the proper distance for another trayful 55

of material to be dropped thereon. This signaling device is represented as comprising the bell crank lever 28 one arm of which is engaged by pins mounted upon the drum 3 and the other 5 arm of which is a switch that serves to close the circuit 29 including the lamp 30. If desired, this device may be located outside of the furnace chamber on an extension of the drum.

While we have shown the gate 7, the carriage 10 15, and the tray bottom 21 all arranged to be operated manually, it will be understood that under certain circumstances we may arrange some or all of these elements of the structure to be moved by power devices, such for example as 15 pneumatic pistons, electric motors, or other well known power actuating means. Where such actuating means is employed, the various operations may be controlled by the bell crank 28 whereby the various parts of the mechanism will 20 operate automatically and in the proper sequence.

We have chosen the particular embodiment described above as illustrative of our invention and it will be apparent that various modifications 25 may be made without departing from the spirit

and scope of our invention which modifications we aim to cover by the appended claim.

What we claim as new and desire to secure by Letters Patent of the United States, is:

In a furnace having a charge receiving opening 5 normally closed by a gate to prevent the escape of a protective atmosphere and having a belt conveyor therein for supporting small articles to be heat treated therein, apparatus for charging said furnace with a minimum loss of said atmosphere and for depositing said articles evenly on said belt comprising a track arranged opposite said opening, a carriage having wheels arranged to run on said track and provided with a tray for said articles having a slidable bottom and 15 having transverse members extending thereacross and a rod connected with said bottom and mounted on said carriage for withdrawing the bottom from the tray, said tray having its sides extending downwardly below the bottom thereof to 20 reach nearly to said belt for preventing said parts from spreading sideways on the belt when released from the tray.
